(57) **CLAIM**

The ornamental design for a pivoting magnetic light, as shown and described.

DESCRIPTION

FIG. 1 is a top perspective view of the ornamental design of a pivoting magnetic light according to the invention;
FIG. 2 is a reverse perspective view of the design of FIG. 1;
FIG. 3 is a side view of the design of FIG. 1;
FIG. 4 is a further side view of the design of FIG. 1;
FIG. 5 is a top view of the design of FIG. 1;
FIG. 6 is a bottom view of the design of FIG. 1; and,
FIG. 7 is a further perspective view of the design of FIG. 1 with the light in a pivoted position.
